LILLIAN TOWY, OF INGLEWOOD, CALIFORNIA

MILK-BOTTLE CAP

Application filed November 7, 1928. Serial No. 317,753.

This invention relates to closures for receptacles, and more especially to an improved type of milk-bottle cap.

An object of the invention is the provision of a novel closure for the opening of a receptacle, this closure having means for facilitating removal thereof when access to the interior of the receptacle is desired.

A more specialized object is the provision of a disc of material having a certain degree of resilience—for example, cardboard—adapted to be inserted in the top of such a receptacle as a milk-bottle, to provide a closure therefor, capable of normally retaining the contents of the bottle, and which is provided with novel means for facilitating the removal of the closure when access to the interior of the receptacle is desired, as for the purpose of filling the bottle or emptying the contents therefrom.

A further object is the provision of a receptacle closure as described, in which the means for facilitating removal, comprises an area of reduced resilience, such as a score extending across the closure, and also provided with means such as a tab affixed to the closure adjacent the said area of reduced resilience, with the result that when this tab is pulled, the closure will buckle along the line of the said area, reducing the effective width of the closure measured along a line perpendicular to the said area, with a consequent loosening of the engagement of the closure with that portion of the receptacle to which it is attached.

Milk-bottle caps have previously been supplied with tabs for facilitating the removal thereof, but it has been found in practice, that the engagement of the closure with the mouth of the bottle, is in most cases, sufficiently secure to result in tearing of the tab from the cap before the cap itself, is loosened from the bottle. It is an object of my invention therefore, to improve upon milk-bottle caps provided with removing-tabs, in such a manner that the removal of the cap is effected without requiring a pulling force to be exerted upon the tab, sufficient to overcome the ultimate strength of the material of which the cap and/or closure is constructed.

A still further object is the provision of a milk-bottle cap having an improved type of removal-tab, this tab being formed by a plurality of pairs of bounding scores whereby the tab may be severed from the body of the closure along all but one edge thereof, and the scores of each pair being upon opposite faces of the closure and slightly offset from each other, facilitating severing of the tab from the body of the closure.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a perspective view of the top of a conventional milk-bottle closed by a cap incorporating the features of my invention.

Fig. 2 is a view similar to Fig. 1, showing the cap with its removing-tab raised to operative position and the cap itself, buckled as in the operation of being removed from the milk-bottle.

Fig. 3 is a vertical sectional view of the upper portion of the bottle and cap of Fig. 2, the plane of section being indicated by the line 3—3 of that figure.

Fig. 4 is a plan view of a bottle cap incorporating the features of my invention.

Fig. 5 is a vertical sectional view taken upon the line 5—5 of Fig. 4.

Fig. 6 is a vertical sectional view taken upon the line 6—6 of Fig. 4.

Fig. 7 is a view similar to Fig. 5, but showing the cap with the removing-tab raised to operative position, and the cap itself, buckled as in the operation of being removed.

The closure of my invention is herein described as being employed to close the mouth 11 of a conventional milk-bottle 12. Receptacles of this nature are commonly closed by a disc of suitable material such as waxed cardboard pressed into the mouth 11. For this purpose a notch 13 is formed in the inner circumference of the mouth of the bottle, this notch 13 being defined by a vertical shoulder 14 and a horizontal shoulder 16. It is cus-

tomary to so dimension the closure disc that its edges are pressed into tight engagement with the vertical shoulder 14 when the closure is pressed into place, providing a sufficiently 5 tight joint between the mouth of the receptacle and the closure, to satisfactorily retain the contents. However, it has been found in order to insure a sufficiently tight seal, the edges of the closure disc must engage the 10 vertical wall 14 so tightly that difficulty is encountered in removing the closure. In fact, even though these closures have previously been supplied with a tab which may be raised and pulled, the engagement of the closure with the mouth of the receptacle, is so 15 tight that the tab will be severed from the closure before the engagement of the closure with the receptacle is broken.

Accordingly, the closure 21 incorporating 20 the features of my invention, has been dimensioned to fit within the space defined by the shoulder 14 with its edges pressed firmly against that shoulder with a sufficient degree of tightness to provide a satisfactory seal. 25 This closure may be formed of any suitable material such as cardboard either waxed or not, according to the particular requirements. However, this material should be possessed of sufficient resilience to retain the closure in 30 shape when it is pressed into the annular notch 13. The form of the closure herein shown and described, is a disc, since it is to be received within the round mouth 11 of a milk-bottle 12. It should be understood 35 however, that in the event a receptacle having a different shaped mouth, is to be closed, the closure may be shaped to conform therewith.

An area of reduced resilience extends 40 across the disc 21. A convenient method of forming this area is by providing a score 22 extending thereacross. Preferably this score 22 is in the inner face of the disc 21 and is disposed diametrically thereof.

45 A removing-tab 23 is also provided so that the removal of the closure 21 may be facilitated by grasping the tab 23 and pulling thereon. This tab 23 is formed by a plurality of bounding scores 26, 27, and 28, in the outer 50 face of the disc 23, and scores 29, 31, and 32 in the inner face. The scores 26 and 29, and the scores 28 and 32, terminate adjacent the score 22 and at points considerably spaced so that the base of the tab 23 or that portion 55 of the tab which is not intended to be severed from the body of the disc, is disposed adjacent the area of reduced resilience. The bounding scores 26 and 29, 27 and 31, and 28 and 32, are arranged in pairs, the scores of 60 each pair being slightly offset from each other as indicated upon Figs. 4, 5, and 6. Preferably each of the scores extends into the associated surface of the disc a distance substantially corresponding to half the thickness of 65 the disc, with the result that when it is desired

to sever all the bounding edges of the tab 23, except the base thereof, from the body of the disc 21, this may be accomplished by tearing the material of which the disc is formed, in a plane parallel to the faces thereof, taking advantage of the laminated nature of the material of the disc in the event that such material as cardboard is employed. A notch 36 70 is formed in the outer face of the body of the disc adjacent the score 27, permitting the insertion of a finger-nail to facilitate severing the tab 23 from the disc. It should be observed that each of the bounding edges of the tab 23 is formed by a pair of scores, with the exception of the base 37 which is defined by the single score 22. Consequently, the connection between the tab 23 at the base 37, is possessed of greater tensile strength than the other connections between the tab 23 and the body of the disc 21. 75

In operation, the closure disc 21 is pressed into the notch 13 of the receptacle 12, in the usual manner, without disturbing the tab 23 from the body of the disc 21. When it is desired to remove the disc 21 in order to open the receptacle, the tab 23 should first be raised as indicated upon Figs. 2 and 6. Then this tab may be grasped and pulled, and since the base of the tab 23 is secured to the body of the disc 21 adjacent the diametrically extending score 22, a tendency will be developed for the disc 21 to buckle, reducing the effective diameter of the disc measured perpendicularly to the score 22, with the result that the disc 21 may be easily withdrawn from the mouth 11 of the bottle 12. 90

It should be further observed, that the tab 23 may be raised, forming an opening 38 in the disc 21, and the disc may be left in its normal position within the mouth 11 of the bottle 12, should it be desired to employ the well known sipping-straws for the removal 95 of the contents of the bottle. 100

It is to be understood that the details of the invention as herein disclosed, are subject to alteration within the spirit or scope of the appended claims. 110

I claim:

1. A milk bottle cap comprising a flat disc of paper or similar material weakened for folding purposes upon a transversely extending line, and a tab for removing the disc, said tab being permanently connected to the disc adjacent the weakened line and normally being disposed in a plane parallel to the plane of the disc. 115

2. A milk bottle cap comprising a flat disc of paper or similar material weakened for folding purposes upon a transversely extending line, and a tab for removing the disc, said tab being formed integral with the disc and normally being disposed in the plane thereof, said tab being adapted to remain permanently connected to the disc adjacent said weakened line. 120 125 130

3. A milk bottle cap comprising a flat circular disc of paper or similar material weakened for folding purposes upon a diametrical line and a tab for removing the disc, said tab being formed integral with the disc and normally being disposed in the plane thereof, said tab being adapted to remain permanently connected to the disc adjacent said weakened line.

10 4. A milk bottle cap comprising a flat disc of paper weakened for folding purposes upon a diametrical line, there being cuts formed on the upper side of said disc extending partially through the disc defining a tab formed integral with the disc adapted to remain permanently connected to the disc adjacent said weakened line.

20 5. A milk bottle cap comprising a flat disc of paper weakened for folding purposes upon a diametrical line, there being cuts formed on the upper side of said disc extending partially through the disc defining a tab formed integral with the disc adapted to remain permanently connected to the disc adjacent said weakened line, there being similar cuts formed on the under side of the disc extending partially through the disc which are parallel to but spaced from the cuts on the upper side of the disc.

25 30 In testimony whereof I have signed my name to this specification.
